UNITED STATES PATENT OFFICE

WILLIAM F. HUCK, OF BROOKLYN, NEW YORK, ASSIGNOR TO R. HOE & CO. INC., OF NEW YORK, N. Y., A CORPORATION OF NEW YORK

PROCESS AND APPARATUS FOR MATRIX ROLLING

Application filed April 21, 1927. Serial No. 185,561.

This invention relates to matrix rolling machines having movable beds and a main pressure roll, and more particularly to means for mounting "ironing out" rollers at the side of the main pressure roll to bear on the work in advance of the main roll, though it is noted that the invention is not limited to use with the particular machine stated.

In making matrices for stereotype plates, a form is made up consisting of type locked in a chase. On this is placed the paper mat which is rolled into the type to take the impression and form a matrix. Over the mat are placed blankets of cork and felt. A frame thus covered is placed on the table of a matrix rolling machine and passed under the pressure roll thereof.

Unless means are taken to prevent it, the blankets will be forced back in the form of a wave in front of the main pressure roll, and one object of the present invention is to provide efficient means to keep the blankets drawn taut in order to insure good work. Said means may be one or more ironing-out rollers or other pressure devices placed longitudinally of the main pressure roll, and another object of the invention is to provide in a device of this kind an efficient arrangement for supporting said means.

Another object of the invention is to provide in an apparatus of this kind efficient means for automatically raising the pressure devices for the mat and blankets to pass thereunder and lowering the devices to press upon the work to prevent said waves.

Another object of the invention is to provide a method and apparatus of this kind which is operative from either side of the main pressure roll and when the type moves in either direction.

Other objects are to provide adjustment for the pressure of the ironing-out rolls and means for limiting their movement.

Still other objects of the invention are to improve generally the simplicity and efficiency of such devices and methods to provide a device of this kind which is economical, durable and reliable in operation, and economical to manufacture and install.

And still other objects of the invention will

appear as the description proceeds; and while herein details of the invention are described and claimed, the invention is not limited to these, since many and various changes may be made without departing from the scope of the invention as claimed in the broader claims.

The inventive features for the accomplishment of these and other objects are shown herein in connection with an improved ironing-out device which, briefly stated, includes a pair of rings respectively frictionally engaged in grooves at each end of the main pressure roll of a matrix rolling machine having a slidable bed adapted to receive type over which is placed the mat and having the pressure roll above the bed. Each ring is provided with lower bearing lugs in which are received end journals of ironing-out rollers disposed at opposite sides of the roll, whereby when said roll is rotated one roller will press upon the work and leave the opposite roller raised ready to receive the next mat.

In the accompanying drawing showing by way of example one of many possible embodiments of the invention,

Fig. 1 is a transverse vertical sectional view, partly in elevation, showing a portion of the rolling machine and the pressure devices attached thereto, the section being taken approximately on the line 1-1 of Fig. 2, looking in the direction of the arrows of said line;

Fig. 2 is a horizontal sectional view, partly in plan, showing the machine as in Fig. 1, the device being shown in plan, the section being taken approximately on the line 2-2 of Fig. 1, looking in the direction of the arrows of said line; and

Fig. 3 is a transverse vertical sectional view, partly in elevation, showing the main roll with ironing-out device attached, the section being taken on the line 3-3 of Fig. 2, looking in the direction of the arrows of said line.

My improved device is shown in combination with a matrix rolling machine comprising a frame 5, a table or bed 6 horizontally slidable thereon, though it is noted that the invention is not limited to use with this particular machine. Bearing brackets 7 on the

frame carry adjustable eccentric bearing bushings 8' (Fig. 2) therein supporting an upper main pressure roll 8 above the bed and having journals 9 carried in said bushings and having projecting ends 10 and 11.

5 A similar lower, pressure roll engaging under the bed has journals journaled in the frame, said journals also having projecting ends. Intermeshing gears 15, 16 (Fig. 1) carried on the projecting ends 11 and a similar end directly beneath, cause the rolls to turn in unison in opposite directions; while a spur gear 18 on the projecting end 19 of the lower roll engages a rack 20 on the lower part of the bed, whereby the bed moves with the lowest part of the upper roll.

10 A vertical power shaft 21 carries a worm 22 thereon engaging and driving a worm wheel 23 on the projecting end 10, whereby said rolls may be rotated and said bed longitudinally moved back and forth.

15 A chase 25 with type locked therein rests on the bed, over which type is placed the paper mat 27 with cork and felt blankets 28 superposed thereon, which mat is rolled into the type by the rolls as the rolls are rotated and the bed moved, thereby to take an impression and form a matrix. Unless means are taken to prevent it, the blankets will be 20 forced back in the form of wave in front of the roller 8, and the main object of the present ironing-out device is to provide means to keep the blankets drawn taut in order to insure good work. This device will now be 25 described.

30 Each end of the upper roll 8 is provided with an annular groove 30 (Fig. 2) there-around in which is disposed a split ring 31, each comprising upper and lower sections 32, 33 (Figs. 2 and 3) respectively comprising 35 end lugs 35, 36, the lower lugs having threaded openings, the upper lugs having unthreaded openings, in which are received screws 37 on which are disposed springs 38 between the screw heads and the upper lugs 35, whereby 40 the rings are adjustably frictionally held in the grooves.

45 Bearing lugs 38' on the ends of each lower section 33 beneath the lug thereof are each 50 provided with a bearing bore alined with the similar bore of the ring at the opposite end of the main roll 8, in which are received end journals 39 of pressure device such as "ironing-out" rollers 40, 41 disposed longitudinally of and at opposite sides of the upper roll 8, whereby when the main rolls are rotated and 55 the bed moved, the rings will, because of the friction, initially turn and tend to rotate with, and in the direction of the upper roll, 60 thereby to lower and press to the blanket, for instance the roller 40 of Fig. 1 adjacent to the mat when the mat is moved, in the direction of the arrow 43, to the main roll, and 65 leave the opposite roller 41 raised, on the side 65 where the mat leaves the main roll, for the

reception of the next mat, which may be inserted from that side.

Spaced stop lugs 43, 44 on the top of the mid part of the upper ring are adapted to engage a stop pin 45 mounted on each main bearing bracket 7 and disposed between said stop lugs, thereby to limit the motion of the rings to prevent either roll from coming too close to the bed.

70 While the herein invention is not limited to the particular rolling machine shown, suitable means are shown for adjustably rotating the eccentric bushings 8'. This means comprises extension brackets 48 on the bearing brackets 7, each carrying an upwardly extending bearing bracket 49 and a head 50 having a vertical bore. An arm 51 carried on each bushing 8 has a transverse bearing opening at its end in which is disposed a cylindrical block 52 having a threaded bore. A screw 53 in the vertical bore of the head 50 has a threaded end in the threaded bore of the block 52 and carries a beveled gear 54 on its upper end. A synchronizing shaft 55 mounted in said upwardly extending bracket 49 80 carries intermediately thereof hand wheels 56, and gears 57 on the ends thereof engaging with said beveled gears, whereby said screws 85 may be simultaneously turned and said bushings 90 simultaneously adjusted.

95 A scale 60 is mounted on the end of each of the arms; and an upright 61 on the frame of the machine is provided with an index 62 cooperating with the scale for accurate adjustment of the arms, the bushings and the 100 upper roll 8.

105 In operation, the form with blankets 28 thereon is placed on the table 6 and pushed in close to the roll 8. When the machine is started to move the bed in the direction of the arrow 43, the friction of rings 31 on roll 8 will cause roll 40 to be brought into contact with the blankets and exert pressure which can be varied by adjusting the screws 37. The blanket is thus held taut and smooth as 110 it enters under the roll 8.

115 It should be noted that while the form is passing through the machine, the roll 40 is pressed down while the roll 41 is raised. When it is desired to roll another form, it 120 can be placed on the table which would then be on the opposite side of the roll 8, the roller 41 being raised will not interfere with the placing of the form. Or, if preferred, the machine can be reversed and the table 6 run back empty, and the next form can be rolled from the same side of the machine as before. In this case, the backward motion of the table would raise the roll 40 and leave the machine ready to insert the new form as before described, and in this case only one roller 125 40 or 41 is necessary, though the invention is not thus limited.

I claim as my invention:

1. In combination, a support means to re- 130

ceive type with a mat thereon; a pressure roll, said roll and means being relatively movable to press the mat to the type; pressing devices disposed at opposite sides of the roll; and means adjustably yieldably connected to said roll and supporting the devices whereby when said roll is rotated one device may move to the plane of the mat to press the mat to the type and remove the opposite device from said plane to leave it spaced therefrom.

2. In an attachment for a rolling machine having a slidable bed and a pressure roll over the bed, a pair of split rings adapted to be frictionally disposed around ends of the roll and each comprising upper and lower sections each comprising end lugs, the lower lugs having threaded openings, the upper lugs having unthreaded openings; screws received in said openings; and springs between the screw heads and the upper lugs, whereby the rings are adjustably frictionally held in the grooves; bearing lugs on the ends of each lower section beneath the lug thereof, each provided with a bearing bore adapted to be aligned with the similar bore of the ring at the opposite end of the roll, and adapted to receive end journals of "ironing-out" rollers adapted to be disposed longitudinally of and at opposite sides of the upper roll.

3. In combination, a frame; a bed slidable thereon and adapted to receive type with a mat thereover; a roll rotary over the bed; a ring frictionally disposed on each end of the roll; rollers at opposite sides of the roll, each having its ends journaled in said rings; each end of the roll having a groove therearound; a split ring disposed in each groove and comprising upper and lower sections each comprising end lugs, the lower lugs having threaded openings, the upper lugs having unthreaded openings; screws received in said openings; and springs between the screw heads and the upper lugs; bearing lugs on the ends of each lower section beneath the lug thereof, each provided with a bearing bore aligned with the similar bore of the ring at the opposite end of the roll; "ironing-out" rollers disposed longitudinally of and at opposite sides of the upper roll and each provided with an end journal engaging in the aligned bearing bores; and means limiting the movement of the rings.

4. In combination, a support means to receive type with a mat thereon; a pressure roll, said roll and means being relatively movable to press the mat to the type; a pressing device disposed at one side of the roll; and means adjustably yieldably pressing the device to the mat.

5. In combination, a supporting means to receive type with a mat thereon; a pressure roll, said roll and means being relatively removable to press the mat to the type; a pressing device disposed at one side of the roll; automatic means for moving said device to

the plane of the mat to press the mat to the type; and means for adjusting the pressure of said device.

6. In combination, a supporting means to receive type with a mat thereon; a main pressure member, said member and means being relatively removable to press the mat to the type; a supplemental pressing device disposed adjacent to the main member; and automatic means whereby when said member is moved in one direction, said device may move to the plane of the mat to press the mat to the type; and means for adjusting the pressure of said device.

7. In combination, a supporting means to receive type with a mat thereon; a pressure roll, said roll and means being relatively removable to press the mat to the type; pressing device disposed at one side of the roll; means frictionally connected to said roll whereby when said roll is rotated in one direction said device may move to the plane of the mat to press the mat to the type; and means for adjusting the friction.

8. In combination, a support means to receive type with a mat thereon; a pressure roll, said roll and means being relatively movable to press the mat to the type; a pressing device disposed at one side of the roll; and means adjustably yieldably connected to said roll and supporting the device whereby when said roll is rotated the device may move to the plane of the mat to press the mat to the type.

Signed at New York, in the county of New York and State of New York, this nineteenth day of April, A. D. 1927.
